UNITED STATES PATENT OFFICE.

LAWRENCE LANGNER, OF NEW YORK, N. Y., ASSIGNOR TO THE DAYTON ENGINEERING LABORATORIES COMPANY, A CORPORATION OF OHIO.

IGNITION SYSTEM.

Specification of Letters Patent. Patented Mar. 19, 1918.

1,259,529.

Application filed September 22, 1913. Serial No. 730,968.

To all whom it may concern:

Be it known that I, LAWRENCE LANGNER, a subject of the King of England, residing at New York city, county of New York, 5 and State of New York, have invented certain new and useful Improvements in Ignition Systems, of which the following is a full, clear, and exact description.

This invention relates to improvements in 10 ignition systems for engines, and more particularly to combined ignition and starting systems for the internal combustion engines of automobiles or the like.

It is a well known fact that magneto ignition systems present desirable features of advantage, in that the intensity of the sparking increases with increased engine speeds. On the other hand, the engine can not be 15 started so satisfactorily with magneto ignition as with vibrating spark battery ignition.

One of the objects of my invention is to 20 permit of starting efficiently with magneto ignition. Another object is to accomplish this without altering the construction of 25 magnetos as placed upon the market to-day by magneto manufacturers.

The universal adoption of self-starting 30 devices for automobiles has caused some controversy as to desirable cranking speeds. Starting device manufacturers making starting devices, which crank at high speeds, claim that there is an advantage in doing so, owing to the possibility of cranking with 35 magneto ignition. However, excessively powerful starting motors are required for this purpose, and the heavy current taken from the battery at the moment of starting is liable to damage the battery. Manufacturers of starting devices which crank at 40 lower speeds claim that they can use a smaller starting device with consequent advantages in economy, efficiency and saving in space, the engine being started upon vibrating spark battery ignition.

A further object of the present invention 45 is to arrange whereby a starting device, cranking the engine at low speeds, will be able to start the engine upon magneto.

A further object of the invention is to 50 increase the efficiency of magneto ignition, generally and particularly in the case where fuel heavier than gasoline is employed.

An additional object of the invention is

to prevent the permanent magnets of magneto ignition machines from losing their 55 magnetism.

In accordance with my invention, I provide electrical means for increasing the 60 sparking strength of magneto ignition machines, and I do this by leading current from a battery or other source of electricity into the magneto. In one embodiment of my invention, I provide the permanent magnet of the magneto machine with one or more electro-magnetic windings, through which 65 the battery current flows, thereby increasing the intensity of the magnetic flux of the machine. In some cases I do not interfere with the construction of magnetos as placed upon the market, but provide an electro-magnet attachment which serves the same 70 purpose.

Some preferred embodiments of the invention are illustrated in the accompanying drawings, in which Figures 1, 2 and 3, are 75 diagrams of different electrical systems, while Figs. 4, 5 and 6, illustrate three forms of electro-magnetic attachments in end illustration, parts being shown in section.

Referring to Fig. 1, the dynamo 1 charges 80 the battery 2, to which is connected the winding 3 of the magneto attachment 4. The winding 3 can be cut-out of circuit by opening the switch 5.

Fig. 2, shows the invention applied to the 85 well known "Delco" system of starting and lighting, described in the application of Charles Franklin Kettering, Serial No. 721,237, filed September 19, 1912. When the starting device acts as a motor to start the 90 engine, the contact 6 is moved to the dotted line position 7. Current then flows from battery 2 through lead 8, motor armature winding 9, series field 10, bar 11, contact 6, 95 bar 12 and lead 13 back to battery.

It will be noted that the contact plate 6 is an L-shaped construction, such that when moved to the dotted line position shown in Fig. 2, the lower part of the plate bridges across the insulating portion shown between 100 the plate 11 and the terminal 11^a. To this terminal 11^a is connected the lead wire 11^b, which connects with the magneto winding 3. By this means, not only does the current come from one side of the battery through 105 the starting motor for the starting opera-

- tion, when the contact plate is shifted to the right in Fig. 6, but also a portion of this current, dividing at the point 11^a, goes through the magneto winding 3 and back 5 to the battery. This increases the intensity of the magneto sparking at the moment of starting, so that if desired, the starting device can crank on magneto with a low cranking speed.
- 10 On returning the contact plate 6 to the full line position of Fig. 1, the starting motor is now acting as a generator, and no further current passes through the magneto winding 3, because the contact is broken by 15 the shifting of the plate 6 to the left in Fig. 2. But, if desired, current can be sent into the winding 3 while the engine is running, by closing the switch 16.
- 17 is the generator armature winding, and 20 18 is the shunt field winding of the "Delco" motor-generator, the construction of which is generally well known, and is described in the Kettering application just above referred to.
- 25 Fig. 3 shows my invention applied to a two unit equipment comprising a separate dynamo and motor. Upon closing the switches 19, current flows from the battery 2 charged by the dynamo 1, into the motor 30 20 and winding 3. When the engine is running and the switches 19 are opened, the magneto may still be energized, if desired, by closing the switch 30.
- In case it is not desirable to alter the construction of the magneto machine, I may provide electro-magnetic attachments adapted 35 to be fitted upon the magneto, so that where a starting device is fitted on an engine equipped with the usual magneto, this same 40 magneto may be employed for the purposes of my invention.
- In Fig. 4, which shows a magneto of the well known Bosch type, I have shown an attachment in the form of a frame or strap 45 21, preferably of magnetic material, which is adapted to fit over the permanent magnets 22 of the machine. This strap is bent around, at each side thereof, to form a housing 23 for a soft iron core 24, and around 50 this core and housing is arranged the winding 3. The terminals 25 serve for screwing the attachment on to the magneto.
- In Fig. 5 the attachment is in form of a non-magnetic brass strap 21^a tied together 55 at the upper end, and bent to provide a housing for the electro-magnet which is maintained in said housing by means of pins 26 extending from the core 27 through holes in the housing.
- 60 Instead of providing a separate core, I may form the strap of soft iron and bend it as shown in Fig. 6 to form the core.
- The increased sparking effect of a magneto ignition system in accordance with the 65 invention, is particularly valuable in con-

nnection with the use of heavy fuels for internal combustion engines. As shown in Fig. 3, the intensity of the spark can be varied at will in accordance with the fuel being used, by means of the rheostat 32.

70 The advantages of using this invention, whether for hand or mechanical starting, or for running conditions, will be apparent to those skilled in the art. Other modifications may be made without departing from 75 the generic scope of my invention.

It will be understood that in the claims which follow I use the term "high tension magneto ignition machine" to mean a machine in which the high tension sparking 80 impulses are actually generated in the machine itself, and not by means of a coil external to the machine, as in low tension ignition machines. By a magneto ignition machine I mean a machine in which the magnetic field is normally derived from a permanent electric magnet.

85 What I claim is:

1. In an ignition system, the combination 90 with a magneto, of a supplementary electro-magnetic device for said magneto; an engine starting device; and means for simultaneously causing the operation of said starting device and energizing said electro-magnetic device.

95 2. In an ignition system, the combination with a magneto, capable of supplying sparks efficient for starting when driven at high speed, and a starting device adapted to drive said magneto at low speed; and means for 100 increasing the sparking efficiency of the magneto.

105 3. In an ignition system, the combination with a magneto, of supplemental means for augmenting the normal sparking efficiency 105 of the magneto, and selective means for utilizing the normal magneto, or the normal plus said supplemental means.

110 4. In an ignition system, the combination with a magneto, of a current supply independent of said magneto; an electro-magnetic device associated with the magnetic field of the magneto and controlled by said independent current supply; and means for opening and closing said circuit so as to 115 temporarily increase the strength of the field of said magneto and thus increase the strength of the current produced thereby.

120 5. In an ignition system for explosive engines, the combination with a magneto, of a starter for the engine; coils around the magnet of said magneto; a current supply independent of said magneto; and means for connecting and disconnecting said current supply to said coils to temporarily increase 125 the magnetic field of said magneto when the starter is operated.

130 6. In an ignition system for explosive engines, the combination with a magneto; of coils associated with the field of said mag-

neto; a source of electric current and a motor in circuit therewith; and means for connecting said motor and current source in circuit with said coils, so as to increase the 5 magnetic field of said magneto when the motor is operated.

7. In a system of ignition for explosive engines, a magneto for connection to the igniting devices of an explosive engine, a motor 10 for starting said engine, a source of current supply for said motor, coils associated

with the fields of said magneto, and means for connecting said coils and said motor simultaneously to said source of supply, as and for the purpose specified.

15

In testimony whereof I affix my signature in the presence of two subscribing witnesses.

LAWRENCE LANGNER.
